UNITED STATES PATENT OFFICE.

GEORGE WALTHER, OF DAYTON, OHIO, ASSIGNOR TO THE DAYTON STEEL FOUNDRY COMPANY, OF DAYTON, OHIO, A CORPORATION OF OHIO.

PRODUCING OF CAST-METAL WHEELS.

Original application filed May 10, 1920, Serial No. 280,217. Divided and this application filed June 16, 1921. Serial No. 478,130.

My invention relates to the producing of cast metal wheels.

The object of my invention is to provide means for a process of producing a cast metal wheel of a type whose construction shall remain unchanged in the essential particulars when it is necessary to adapt the construction to varying sizes of axles, bearing, etc.

At the present time, cast wheels, and in particular cast steel wheels for automotive equipment, are subject to the objection that radical modifications in the patterns must be made to fit each cast steel wheel to the particular type of axle and bearing with which the wheel is to be fitted according to the desire of the individual manufacturer of the automotive equipment. This seriously disturbs economical production in the foundry.

It is an object of my invention to provide means and process to produce a wheel of such construction which will reduce these difficulties to a minimum by preserving the spokes and rim and hub in the exterior dimensions in the same form, shape and dimensions for each type of axle and each width of rim. The only variation that will be made will be in the width of the rim and the interior diameter of the hub and the width of the hub without disturbing the exterior diameter.

In my present invention I desire to claim the means and process by which I am enabled to produce wheels of different hub diameters, hub widths and varying rim dimensions with the same spoke core comprised of a single unit.

To this end I provide a one piece spoke core which may be used with hub cores of varying width as set forth in my co-pending application, Ser. No. 363,941 and adapted to have sections placed thereon at the rim portion of the wheel to vary the dimensions of the rim and thereby produce a wheel adequate to the capacity to which it is to be applied.

Fig. 1, is a side elevation of a vertical section of the standard wheel taken on its longitudinal axis.

Fig. 2, shows the master pattern with detachable members to form the hubs of varying width.

Fig. 3, is an enlarged view of the rim.

Fig. 4, is a side elevation of a vertical section of the core box and a core with the removable filler.

Fig. 5, is a section of the standard hub illustrating by the dotted lines a hub extended which, while preserving the outside dimensions of the hub, has extended its width and narrowed the internal diameter of the hub.

Fig. 6, is a vertical sectional view of the flask, cores and metal wheel.

Referring particularly to Figure 1 showing a section of a wheel produced by my improved process, 1 is the outer periphery of the rim, 2 is the wall of a slot cut in the outer periphery which is bridged at intervals by the bridges 3—3. 4 is a spoke whose outer ends merge into an arch with the rim marked 5 in Figure 3. The wall 4 of the spoke has a supplementary rib 7 which serves as an additional support on the inside of the hub next to the vehicle for the inner hub wall 6. This inner hub wall 6 proceeds outwardly to the outside of the wheel until it meets the face of the outer wall 8 of the hub on the outside of the wheel. This wall 8 is supported and joined to the spoke 4 by a curving wall 9 whose curvature in this standard wheel and location with respect to the spokes remains constant while the distance between the wall 6 and 9, and consequently the length of the wall 8, varies according to the internal diameter of the hub. This internal diameter of the hub depends upon the particular axle and bearing which may be used with this standard type of wheel.

Upon the face of the wall 8 is mounted a hub cap.

In this art it has been found very desirable to have a uniform and standard hub cap which may be used with varying sizes of axles and therefore varying sizes in the internal diameter of the hubs of the cast wheels.

By my method of manufacture, I am enabled to project laterally the hub to take varying lengths of axle without disturbing the curvature of the wall 9, therefore permitting, as shown in Figure 5 of the use of the same hub cap with varying sizes of hub.

In my present invention, I have accomplished the result also of varying the internal diameter of the hub without disturb-

ing the standard construction of the wheel. To produce varying diameters of the hub internally without disturbing the master patterns and the course of manufacture, I provide fillers of varying diameters to co-operate with the master pattern whereby varying internal diameters will be produced, ranging from the maximum diameter of the master core box itself to the minimum diameter secured by the use of the various fillers of varying dimensions, placed in the core box.

Referring to Figure 2, 10 is the master pattern, 11 is a detachable hub piece of the pattern and 12 is another detachable hub piece. Hub pieces of varying lengths all fitting on the shoulders 13—13 may be installed on the master pattern without modifying them to secure varying widths of hubs.

This pattern is used to form the impression in the sand which will determine the outside dimensions of the rim, spoke and hub width.

25 The internal diameter of the hub may be varied to suit the desire of the manufacturer of the wheel without disturbing the curvature of the wheel at 9 in Figure 1. The walls 6—6 of the wheel are either brought closer together or put farther apart according to the desire of the manufacturer to adapt his wheel to a particular axle and bearing. This results in a corresponding change in the length of the wall 8 and of course of the support 7.

In the course of manufacture, it is essential to disturb the progress of manufacture as little as possible to secure varying types of hubs for varying types of axles and bearings. It is also desirable to have the same external face for each wheel in order that the same hub cap and same odometer may be used for varying types of axles, with the corresponding variations in the wheels.

40 This is accomplished in my invention by maintaining the curvature of 9 and projecting that wall outwardly, maintaining the same face 8 and only modifying 8 as to its length. This can be seen in Figure 5, where such a projection has taken place as shown by the dotted lines. The dotted lines show a construction of hub where the axle is longer and the clearance between it and the walls of the hub is narrower than that in the case of the axle and hub shown in full lines.

45 To manufacture readily such a wheel, which can be thus modified in these particulars without disturbing the orderly course of quantity production, I employ a core for the hub, spoke and rim of the cast wheel, which is made as follows:

50 Referring to Figure 4, 14 is a core box and 15 is a central portion of a core box

which determines the minimum diameter of the hub. The outer walls of 15 determine the position of the inner wall of 6 in the wheel. I also employ a filler 16 which may be used to increase the diameter of the hub between the walls 6—6. Fillers of the character of 16 fit around the master portion of the core at 15. These fillers always have the same internal diameter, but may be of varying external diameter, which will result in different size cores and therefore different diameter of hub. 17 is the core thus formed and 18 is the parting line of the core.

With the master pattern, I have determined the outside dimensions of the rim, spokes and hub width of the prospective wheel.

With the arrangement in Figure 4, I have determined the inside dimensions of the wheel, having made the core 17 for that purpose. With the detachable members 12 and 11 of Figure 2, I vary the width of the hub and with the detachable fillers 16 of Figure 4, I vary the internal diameter of the hub.

55 Referring to Figure 6, it will be seen that I have provided means for varying the dimensions of the rim of the wheel. 19 designates the wall of the drag portion of the flask and 20 the wall of the cope which will clamp together, as shown at 21. The sand in the drag is indicated at 22. Preparatory to pouring the metal the spoke core 17, which is made in one piece as distinguished from the old segmental spoke cores, is positioned in the sand 22 and supported by the print 23 and suitable chaplets, adapted to be placed in the openings 24. The desired size of hub core as shown at 100 25, is then positioned with respect to the spoke core. In case it is desired to increase the width of the rim a series of supplemental cores 26 are pasted on to the one piece spoke core 17, as shown at 27. It 110 will readily be seen that this means of increasing the rim has great advantage in that the same spoke pattern may be used to produce wheels having rims of the desired size. Furthermore, this method of increasing the rim reduces the amount of metal that formerly was necessary in making cast metal wheels, of the corresponding rim size and at the same time produces a rim structure of the desired thickness of metal throughout, which obviates all the difficulties heretofore experienced of weakening the structure due to the unequal thickness of the metal and the consequent cooling with pores or blisters therein. Similar paste-ons may 115 also be utilized to reduce the amount of metal in the spoke at the hub portion of the wheel.

120 It will be seen that the wheel is maintained in its standard dimensions elsewhere,

that it can be readily modified in the particulars which are necessary without otherwise disturbing the patterns, core boxes, etc. and that my invention results in a productive course of manufacture with the minimum of modification of the articles necessary to accomplish the desired object.

I desire to comprehend within my invention such variations as may be within its scope without limiting myself to the specific embodiments of it illustrated here.

This application is a division of my application Serial No. 380,217, filed May 10, 1920.

Having thus fully described my invention, what I claim as new and desire to secure by Letters Patent, is:—

1. The method of forming a core for use in casting wheels with hubs of varying width but having the same wheel peripheral diameter which consists in making the major portion of the core in one piece and applying to said core members to vary the width of the hubs of the wheels to be cast.

2. The method of forming a core for use in casting wheels which consists in making the major portion of the core in one piece and thereafter applying to said core means for increasing the width of the rim of the wheel to be cast.

3. The method of forming a core for use in casting wheels which consists in making the major portion of the core in one piece and thereafter applying to said core means for reducing the amount of metal required to provide a wheel of the desired dimensions.

4. The method of forming a core for use in casting wheels which consists in making the major portion of the core in one piece and thereafter applying to said core means for increasing the width of the rim and other means to vary the internal diameter of the hubs of the wheels to be cast.

In testimony whereof, I affix my signature.

GEORGE WALTHER.
